(57) **CLAIM**

The ornamental design for a garment bag, as shown and described.

DESCRIPTION

FIG. 1 is a perspective view of a garment bag showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof;

FIG. 8 is inside view thereof, shown with the garment bag in opened position; and,

FIG. 9 is another inside view thereof, shown with the garment bag in further opened position.

The broken lines illustrate portions of the garment bag that form no part of the claimed design.
